Physics, Inc., Mountain View, Calif., a corporation of
California

Filed Oct. 11, 1966, Ser. No. 4,234

Term of patent 14 years

(Cl. D26—14)

FIG. 1

FIG. 2

FIGURE 1 is a right side, top and front perspective view of a gas laser, showing my new design;

FIGURE 2 is a right side, bottom and rear perspective view;

FIGURE 3 is an enlarged fragmentary top plan view, with portions of the elongated apertured elements omitted for ease of illustration;

FIGURE 4 is a fragmentary right side elevational view to the same scale as FIGURE 3, the two sides being substantially identical in appearance; and

FIGURE 5 is a front elevational view to the same scale as FIGURES 3 and 4, the rear being substantially identical in appearance to the front.

I claim:

The ornamental design for a gas laser, as shown and described.
